INVENTOR.

Beecher Frank.

BY John A. Bonnhardt

ATTORNEY.

UNITED STATES PATENT OFFICE.

BEECHER FRANK, OF CLEVELAND, OHIO, ASSIGNOR TO THE SAFETY CLOTHING COMPANY, OF CLEVELAND, OHIO.

LEGGING.

Application filed March 24, 1924. Serial No. 701,488.

To all whom it may concern:

Be it known that I, BEECHER FRANK, a citizen of the United States, residing at Cleveland, in the county of Cuyahoga and State of Ohio, have invented certain new and useful Improvements in Leggings, of which the following is a specification.

This invention relates to improvements in leggings, particularly to that type designed for use in and about foundries and the like where the wearer's legs are exposed to intense heat.

It has heretofore been impossible to induce the operators to wear leggings around these places because the construction was such as to render them extremely uncomfortable and furthermore the steel fastening means soon became heated and consequently were injurious to the wearer.

It is the primary object of this invention to so design a legging that it will be adjustable to the wearer's legs and may be comfortably worn, and to eliminate steel or other metallic stays etc.

It is likewise an object to provide fastening means for a legging which may be easily manipulated for application and removal of the legging.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

Fig. 1. is a plan view of a legging constructed in accordance with this invention.

Fig. 2. is a side elevation showing the legging substantially in the position assumed when upon the wearer's leg;

Fig. 3. is a view showing the manner in which the edges overlap and the relative position of the several parts, and

Fig. 4. is a sectional view taken substantially on the line 4—4 of Figure 2.

Having more particular reference to the drawing, this improved legging may be stated as comprising a main body portion 5 which obviously may be formed of any of the usual materials employed in making up garments of this nature, and having attached to its lower end and substantially midway its width an instep covering portion 6. As

is apparent, in this construction a portion 55 of the lower end of the body 5 is cut away, and to the edge of this cut away portion the instep covering member 6 is stitched or otherwise attached.

The remaining portions of the lower edge 60 of the body 5 are cut so that the complete legging will snugly fit about the wearer's ankles. As shown in the several figures, vertically extended pockets 7 are formed upon the inner forward portion of the body 65 for the purpose of receiving stiffening members whereby to give shape to the legging.

At one vertical side of the legging the material is folded upon itself and stitched in a manner to form a pocket 8, which as shown converges downwardly and is adapted for the reception of a fastening strip or stay 9 made up of fibre or the like material. This member is so made as to absorb a minimum amount of heat and to offer the least resistance to the various movements of the wearer. The result is that an unusual degree of comfort is afforded the user. Immediately above the upper end of the fastening element 9 is an extension or tongue which as 80 shown carries one portion 11 of a separable fastener.

Arranged at spaced points near the edge of the legging opposite the aforesaid tongue 10 is a set of fastening elements 12 which 85 obviously are in the form of portions of separable fasteners adapted to coact with the other portion 11.

Arranged upon the outer side of the body portion 5 and at a point opposite the extended end of the fastening strip 9, is a set of spaced pockets 13 which are formed through stitching to this body portion a short length of material.

In attaching this legging to the leg of an operator the body portion is first positioned about the leg; the lower or extended end of the fastening strip 9 is inserted into one of the pockets 13, and the portion 11 of the separable fastener is then engaged with one of the other portions 12. At this point the legging is securely attached to the leg of the wearer and he is assured of comfort due to the yieldability of the fastening strip or stay 9, and the stiffening members 7. As heretofore stated this legging as now constructed is capable of adjustment to legs of different sizes and furthermore includes no

metal pieces and stays which would be quickly heated and consequently injure the operator.

Manifestly certain minor changes in some details of construction may be resorted to as will fall within the scope of the appended claim and these changes I consider within the spirit of my invention.

I claim:

10. A legging formed of fire proof material and comprising a body portion having vertical edges designed to be overlapped, one edge portion being shorter than the remaining body portion and having a vertical

tapering pocket, a tapered stay arranged in 15 said pocket and extending therebelow, a tongue formed at the upper end adjacent the pocket, snap fasteners carried by said tongue and adjacent portions of the legging to permit adjustment to the leg of a wearer, a set 20 of circumferentially spaced vertical loops arranged to receive the lower end of the stay to secure the lower portion of the legging together, and an in-step covering portion carried by the legging.

In testimony whereof, I affix my signature.

BEECHER FRANK.
